UNITED STATES PATENT OFFICE

2,078,154

PLUG AND CAP CONNECTER

Shigeo Okino, Honolulu, Territory of Hawaii

Application November 13, 1935, Serial No. 49,569

1 Claim. (Cl. 173—343)

This invention relates to plug and cap connectors and has for an object to provide a device of this character wherein the prongs of the cap may be inserted in a novel annular contact carried by the plug by other than straight line movement.

A further object of the invention is to provide the cap and plug with center contacts which permit of the members being assembled and disassembled without binding or injury to the parts under the most severe conditions of service.

A further object is to provide a device of this character which will be formed of a few strong, durable and inexpensive parts, which will be easy to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a front elevation of a plug and cap connector constructed in accordance with the invention and showing the parts separated.

Figure 2 is a vertical sectional view of the cap.

Figure 3 is a bottom plan view of the cap.

Figure 4 is a top plan view of the plug, and

Figure 5 is a detail perspective view of the annular contact carried by the plug.

Referring now to the drawing in which like characters of reference designate similar parts in the various views, 10 designates a plug having an annular recess 11 and an axial recess 12 formed concentrically in the top face, the latter having a flared mouth to promote easy entry of the center terminal of the associated cap.

An annular contact 13 is disposed in the recess 11 and preferably the contact is formed of an endless channeled metal band of good electrical conductivity and includes an outer flange 14, an inner flange 15, and a web 16 connecting both flanges. The inner flange is imperforate while the outer flange is formed with a plurality of slits 17 which extend from the top edge of the flange to approximately the web and provide resilient tongues 18 around the entire periphery of the contact. The tongues are deformed inwardly above the web to provide V-shaped projections 19 which snap into similar shaped recesses 20 formed in the prongs 21 of the cap 22 as will later be described.

A threaded terminal 23 is disposed on the exterior of the plug below the contact and is electrically connected to the contact by wires 24, two of such wires being shown in Figure 2, although as many wires may be employed for this purpose as is desired.

The cap 22 is provided with a forked axial opening 25 to receive the circuit wires, the branches 26 of the opening communicating with a recess 27 formed in the bottom face of the cap. The prongs 21 are disposed between the branches and the rim of the cap, as shown in Figure 3, and each is provided with a circumferentially grooved head 28 which is imbedded in the material of the cap and firmly anchors the prong to the cap. Both prongs are connected by a semi-circular metal connector strip 29 into which is threaded a screw 30 for attaching one of the circuit wires.

The cap is provided with a center terminal comprising a circumferentially grooved head 31 which is imbedded in the material of the cap, a pin 32, and a cylindrical tip 33, there being a sleeve 34 of insulating material disposed on the pin 32 extending from the head to the tip, as shown in Figure 2. The head 31 is provided with a lateral metal arm 35 which extends radially along the bottom of the recess 27 and a screw 36 is threaded into the end of the arm 35 to receive the other circuit wire as will be understood.

A metal cup 37 is disposed in the bottom of the center recess 12 of the plug and the cylindrical side wall of the cup is deformed to provide a V-shaped projection 38 which is adapted to spring into a groove 39 in the tip 33 of the cap center terminal and yieldably lock the cap to the plug. The cup is slit at intervals, as shown at 40, to make the cup resilient. A pin 41 is formed integral with the bottom of the cup and extends through an axial opening 42 in the plug. The pin terminates in a disc head 43 which forms the center terminal of the plug.

In operation the cap may be applied to the plug by merely inserting the tip 33 of the center terminal in the recess 12 of the plug and then pressing upon the cap to engage the prongs 21 with the resilient tongues of the contacts 13 and such pressure may be applied while swiveling the cap axially, as no care need be taken to guide the prongs into a pair of contacts as is customary in applying the cap to ordinary plugs.

From the above description it is thought that the construction and operation of the invention will be fully understood without further explanation.

What is claimed is:

A connector including a plug having an annular recess in one end face, a channeled metal annulus in the recess having spaced circular flanges and a web connecting the flanges, the outermost flange being slit from the edge to approximately the web to form spring tongues, said spring tongues being provided with transverse V-shaped

projections on their inner faces adapted to enter correspondingly shaped recesses in the prongs of a cooperating cap and lock the cap to the plug, a threaded terminal disposed on the exterior of the plug and electrically connected to the annulus, 5 and a center terminal disposed axially in the plug.

SHIGEO OKINO.
